ATTORNEY

UNITED STATES PATENT OFFICE.

WILLIAM W. HAYDEN, OF NEWARK, NEW JERSEY.

DESIGN FOR A HANDLE FOR CUTLERY, &c.

SPECIFICATION forming part of Design No. 21,811, dated August 30, 1892.

Application filed July 20, 1892. Serial No. 440,679. Term of patent 3½ years.

To all whom it may concern:

Be it known that I, WILLIAM W. HAYDEN, a citizen of the United States, and a resident of Newark, in the county of Essex and State 5 of New Jersey, have invented and produced a certain new and useful Design for a Handle for Cutlery, of which the following is a specification.

The accompanying drawing, forming a part 10 of this specification, and to which reference is made, illustrates my newly-designed handle for cutlery and other articles.

The handle A at its edges shows the outward 15 curves *a a* and *b b* and the rounded corners *c c*, which meet and form a notch *d* at the end. It also shows the inward curves *e e*, *f f*, and *g g*. At the curves *b g c* appear at the edges of the handle the relief ornaments *f' f'*, of

foliated and scroll order, wrapped around the curved edges of the handle. These terminate at the crossed scrolls *h i* at or about the center of the handle. The scroll *i* forms a part of the leaf ornament *i*, which extends along the center of the handle and joins the scroll *j*. Another similar scroll *j'* appears opposite *j*, as shown. The end of the handle adjacent to the notch *d* is ornamented with scrolls *k k* and a central leaf *l*.

What I claim is—

The design for a handle for cutlery, substantially as herein shown and described.

WILLIAM W. HAYDEN.
